(57) **CLAIM**

The ornamental design for a globe lantern, as shown and described.

DESCRIPTION

FIG. 1 is a front view of a globe lantern showing my new design;

FIG. 2 is a back view thereof;

FIG. 3 is a left side view thereof;

FIG. 4 is a right side view thereof;

FIG. 5 is a downward plan view thereof;

FIG. 6 is an upward plan view thereof; and,

FIG. 7 is a perspective view thereof.

Broken lines are used to illustrate features of the globe lantern which form no part of the claimed device.
